UNITED STATES PATENT OFFICE.

BENJAMIN F. MCGUINNESS, OF SAUNDERSVILLE, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

1,360,553.

Specification of Letters Patent. Patented Nov. 30, 1920.

Application filed May 25, 1918. Serial No. 236,460.

To all whom it may concern:

Be it known that I, BENJAMIN F. MCGUINNESS, a citizen of the United States, residing at Saundersville, in the county of 5 Worcester and State of Massachusetts, have invented a new and useful Weft-Detecting Mechanism, of which the following is a specification.

This invention relates to weft detecting mechanism of the type used to indicate substantial exhaustion of weft in a weft replenishing loom.

It is one object of my invention to provide detecting mechanism so constructed that ample time will be allowed for the indicating movements and for the operations controlled thereby. With this object in view, a feature of my invention relates to the provision of a controlling member normally inoperative but movable to operative position after indication of substantial weft exhaustion, and remaining in such position until the actuator controlled by said member has completed its operative movement.

25 Another feature relates to the provision of resetting devices associated with said actuator and operative on the return movement thereof to reset the weft detector.

Another object of my invention is to provide devices for withdrawing the detector during the transfer of the weft carrier, so constructed that a second and unnecessary indication will be avoided.

An additional object of my invention is to provide detecting mechanism having a certain amount of lost motion, whereby accidental slight indications will not result in a transfer.

Features of my invention also relate to arrangements and combinations of parts hereinafter described and more particularly pointed out in the appended claims.

A preferred form of my invention is shown in the drawings, in which—

45 Figure 1 is a front elevation of a portion of a loom having my improved detecting mechanism mounted thereon;

Fig. 2 is a plan view of the detecting mechanism in normal position;

50 Fig. 3 is a left-hand side elevation of the parts shown in Fig. 1, but in position to call a transfer, and

Fig. 4 is a partial plan view showing certain parts in an intermediate position.

Referring to the drawings, I have shown 55 a bracket 10 (Fig. 1) secured to a loom side 11 and supporting the several parts of my detecting mechanism. I have also shown a portion of a weft carrier magazine frame 12 upon which is mounted a transferrer 13. 60 The mechanism for controlling and actuating the transferrer forms no part of my invention and may be of any usual construction.

A stand or guide-way 14 (Fig. 2) is ad- 65 justably secured to the bracket 10, and a hollow slide 15 is mounted for longitudinal movement therein. At its rear end the slide 15 is provided with a fixed detecting member 16 adapted to engage the weft carrier in 70 the active shuttle. A second detector 17 is formed as a long bent lever pivoted at 18 in the slide 15. The rear end of the detector 17 is provided with teeth adapted to engage the weft on the active weft carrier 75 in the usual manner. A light spring 19 normally holds the detector 17 in the position shown in Fig. 2.

The front end of the member 17 is bent or offset laterally, and is provided with a 80 depending portion 20 (Fig. 1) adapted under certain conditions to engage an arm 21 mounted on a shaft 22 supported in fixed bearings 10^a on the bracket 10. A second arm 23 is adjustably secured to the shaft 22 85 and has a pivoted connection at its upper end with a rod 24, longitudinally movable in a bearing 25. A slot 26 intersects the path of movement of the rod 25 and constitutes a vertical guide-way for one end of 90 an actuator lever 27 pivoted at 28 to the upper end of an actuator rod 29. The opposite end of the lever 27 is pivotally connected at 30 to a rod 31 through which the weft replenishing mechanism is controlled. 95

The rod 29 is given a reciprocating movement from any convenient driven part of the loom, and as long as the rod 24 is withdrawn from the slot 26 the lever 27 swings idly about its pivot 30. When the rod 24 is interposed in the path of the lever 27 the rod 31 is drawn downward, and substantial weft exhaustion is thus indicated to the transfer mechanism.

For a full description of the construction 105 and operation of the lever 27 and parts controlled thereby, reference is made to the patent to Ryon, No. 972,722, issued October

11, 1910. In the claims appended to this specification the lever 27 is termed an actuator, and the rod 24 is designated a controlling member.

5 A stud 32 (Fig. 3) is formed on the side of the arm 23, and a link 33 is connected at its upper end thereto. A spring 34 is connected at one end to the lower end of the link 33 and at its other end to a stud 35 fixed 10 in the bracket 10. The studs 32 and 35 are so positioned that the spring 34 acting through the link 33 yieldingly holds the rod 24 in either operative or inoperative position. In Fig. 3, the arm 23, the rod 24, and 15 the parts connected thereto are shown in operative position to indicate substantial weft exhaustion.

An arm 36 (Fig. 1) is pivoted on a stud 37 fixed in the bracket 10 and is yieldingly 20 moved toward the casing 14 by a coil spring 38. An adjusting screw 39 engages a portion of the casing and limits rearward movement of the arm. At its upper end the arm 36 is extended laterally and upwardly in 25 each direction to form projections 40 and 41. The projection 40 is positioned for engagement with the offset portion of the detecting member 17, and the projection 41 has a slot and screw connection with a sliding bar 30 42 (Fig. 2). The rear end of said bar is guided on a stud 43 in the slide 15, and is provided with an offset portion 44 positioned for engagement by a lug 45 on the arm 46 of the transerrer 13. The casing 14 is slotted 35 to permit movement of the stud 43.

The arm 23 has a depending offset portion 47 (Fig. 3) positioned for engagement by an arm 48 extending forwardly from the actuator rod 29.

40 Having described the construction of my improved detecting mechanism, I will now describe its operation.

The detectors 16 and 17 normally occupy the position shown in Fig. 2, and are held in 45 engagement by the spring 19. When contacting with a weft carrier having a sufficient amount of weft thereon, the weft engages the teeth of the detector 17 and prevents movement thereof axially of the weft carrier. The slide 15 and detectors 16 and 50 17 therefore move idly forward with the weft carrier, and no transfer indication is given.

When the weft is substantially exhausted 55 on the active weft carrier, the teeth of the detector 17 no longer engage the weft and the detector 17 is therefore free to swing laterally as the slide is forced forward by the weft carrier, such lateral movement being due to the engagement of the offset portion 60 of the detector 17 by the projection 40 on the arm 36. The spring 38 is of sufficient strength to overcome the resistance of the light spring 19.

65 The parts are moved forward by the lay to

the position shown in Fig. 4 with the arm 21 then standing in the path of the depending portion 20 of the detector 17. As the slide 15 moves rearward with the lay after the detecting beat, the portion 20 engages 70 the arm 21 and moves the controlling rod 24 to the position shown in Fig. 3 in which position the parts are yieldingly retained by the spring 34. The parts remain in this position until after the downward movement 75 of the actuator rod 29 by which the actuator 27 is moved to indicate a transfer. Upon the next upward movement of the rod 29 the arm 48 engages the portion 47 of the arm 23, as shown in Fig. 3, and returns the 80 rod 24 to the normal inoperative position of Fig. 2.

As the transerrer 13 is subsequently operated to transfer the fresh weft carrier, the stud 45 on the transerrer arm 46 engages 85 the end 44 of the slide bar 42 and moves the bar toward the front of the loom. The slotted connection with the slide 15 permits the bar to move the arm 36 before it moves the slide 15. The pressure of the arm 36 90 is thus removed from the detector 17, which is thus permitted to remain in inoperative position while the slide is withdrawn during the transfer. A second and uncalled for indication by the detector 17 is thus avoided. 95

The projection 20 of the detector 17 is normally slightly spaced from the path of the arm 21, as indicated in Figs. 1 and 2, so that slight movements of the detector 17 will not call for a transfer. Such slight movements 100 are frequently caused by inequalities in the weft surface of the active weft carrier.

Having thus described my invention, it will be seen that the rod 24 is normally maintained in inoperative position and that when 105 moved to operative position it remains in such position until after the operation of the actuator 27. In this way ample time is provided for all necessary operations. It will be further evident that changes and modifications can be made in my invention without departing from the spirit and scope thereof as expressed in the claims, and I do not wish to be otherwise limited to the details herein disclosed, but what I do claim is:— 110

1. In a loom, a stand, a slide freely movable therein, a weft detecting member extending forward longitudinally through said slide and pivoted thereto near the front end of said slide, said detecting member having 115 an off-set front end portion and having a spring acting continuously to hold said detector normally in inoperative position, and a second and stronger spring effective to overpower said first spring and to move said detecting member to operative position when said member engages a substantially exhausted weft carrier.

2. In a loom, a weft detector mounted on a stationary part of the loom, weft replenish- 130

ing mechanism controlled thereby, connections between said detector and said mechanism, indicated for operation on the forward movement of the detector and operative only on the return movement of said detector after an indication of substantial weft exhaustion, and means to reset said detector during weft replenishment and by said weft replenishing mechanism.

10 3. In a loom, a weft detector, and weft replenishing mechanism controlled thereby, said mechanism including an actuator, having an indicating stroke, a normally inoperative controlling member, means controlled by said detector effective to move said member to operative position, means to hold said member in such position, and means operable on the alternate stroke of such actuator effective to restore said member to in-
15 operative position.

4. In a weft detecting mechanism, an actuator, a controlling member therefor, a single means to hold said member in either operative or inoperative position, means to move said member to operative position, and 25 a device operable by said actuator on its stroke effective to restore said member to inoperative position.

5. In a weft detecting mechanism, a slide, a detector pivoted thereon, an arm yielding- 30 ingly engaging said slide, a bar connected to said arm and having a lost motion connection with said slide, and a transerrer having a portion engaging said bar in the event of transfer and withdrawing said arm and said 35 slide successively from operative position.

In testimony whereof I have hereunto affixed my signature.

BENJAMIN F. McGUINNESS.
